UNITED STATES PATENT OFFICE

2,555,253

SUCTION CLEANER

Eugene L. Snyder, Canton, Ohio, assignor to The Hoover Company, North Canton, Ohio, a corporation of Ohio

Application August 21, 1946, Serial No. 691,984

3 Claims. (Cl. 183—59)

1

The present invention relates to suction cleaners in general and more particularly to a new and improved filter-cleaning mechanism in a suction cleaner.

An object of the invention is to provide a new and improved suction cleaner. Another object is to provide a filter vibrating mechanism in a suction cleaner to dislodge dirt from the filter. A further object is to provide a filter vibrating mechanism to receive a force applied by the operator's hand or foot and including means to displace the operator applied force. Another object is to provide a collapsible device for removing the operator's hand or foot employed in operating a filter-shaking mechanism. Other objects and advantages of the invention will be apparent from the following specification and drawings, wherein:

Figure 1 is a longitudinal section partly in elevation of the suction cleaner;

Figure 2 is a section along the line 2—2 of Figure 1;

Figure 3 is a bottom plane view;

Figure 4 is a section along the line 4—4 of Figure 1;

Figure 5 is a view similar to Figure 1, but showing the cleaner casing upended into filter-shaking position and the filter-shaking mechanism at one end of its stroke;

Figure 6 is a sectional view of a modified filter-shaking handle;

Figure 7 is a side elevation of the modified filter-shaking handle in operating position; and

Figure 8 is a section along the line 8—8 in Figure 6 and showing the filter-shaking handle in inoperative position.

The embodiment of the invention disclosed in Figures 1 to 5 comprises a casing 10 closed at its exhaust end by a cap 11 having an outlet port 13 adapted to receive the cleaner end of an unshown hose provided at its opposite end with a surface-cleaning tool in a manner well known in the art. The suction end of the casing 10 is closed by a removable end cap 14 provided with an inlet port 15 adapted to receive the cleaner end of the surface cleaning unit in the same manner as the outlet port 13. End cap 14 is removably attached to the casing 10 by being provided at its lower end with a protruding lip 16 which seats within a pocket 17 formed at the end of a bracket 18 mounted on the bottom wall 19 of the casing 10. A latch 20 is mounted on the top of the casing 10 and cooperates with the end cap 14 to force it against the end wall or face 21 of the casing 10, and a seal 22 prevents leakage of air therebe-

2

tween. Provided along the top of the cleaner casing is a handle 24 by which the operator can lift the cleaner from place to place. The cleaner casing is supported on and spaced from a supporting surface by a pair of runners 25, the front ends of which terminate short of the front end wall 21 of the casing 10.

Within the casing 10 is a motor 26 and a fan chamber 27 in which are suction-creating fans 10 driven by the motor 26. The motor-fan unit is supported at its forward end by a resilient rubber ring 28 which lies around the forward edge of the fan chamber 27 and is carried by a fixed bulkhead 29 in the casing 10. At its opposite end 15 the motor-fan unit is carried by a perforated bulkhead 30 fixedly secured in the casing 10.

On the suction side of the motor-fan unit and between the bulkhead 29 and the cover 14, is positioned an air-permeable dirt bag 31. The filter bag has a side wall 32, a closed end wall 33 and an open end, the latter being secured to an annular flange 34 defining an inlet to the bag, the inlet being flush with the end wall 21 of the cleaner casing.

25 Disposed within the filter bag adjacent the closed end wall 33 is a bag frame 35 provided with an annular flange 36 of a diameter equal to the bag to stretch thereover the bag end wall 33, and the bag is secured to the flange by a clamp 37. The bag frame 35 is perforated for the passage of air through the end wall 33 of the bag.

The filter bag shaking mechanism includes a slide or push bar 40 disposed between the casing 35 flat bottom wall 19 and the motor-fan unit and is slidably enclosed in a guide casing 41 secured to the casing flat bottom wall 19 by rivets 42. The guide casing 41 is sealed at 43 about the bulkhead 29 to prevent leakage of air therebetween. Integral with and normal to the slide 40 is a bag supporting rod 44 which extends between the bulkhead 29 and the end wall 33 of the bag and is connected to the center of the bag frame 35 and the closed bag end wall 33 by a bolt and a wing nut 45, the latter being accessible from the interior of the bag to removably connect the bag. The bag-supporting rod 44 thus supports the closed end 33 of the bag. A guide rod 46 is connected to one end of the slide bar 40 as by welding and the opposite end of the guide rod is slidably supported in a bracket 47 welded to the casing bottom wall 19, and the guide rod 46 forms an axial extension of the slide 40 and is arranged between the filter bag 31 and the casing flat bottom wall 19. A spring

48 is coiled about the guide rod 46 between the bag-supporting rod 44 and the bracket 47 and at all times exerts a force on the slide 40 to move it and the bag-supporting rod 44 toward the rear end cap 11, and thus the bag frame 35 to thereby maintain the filter bag taut.

To effect movement of the slide 40 there is provided a handle 50 or knob mounted upon a pin 51 secured to the slide 40, and the pin 51 passes through a slot 52 in the bottom wall 19 of the casing and also through slots 53 and 54 in the guide casing 41, and these slots are sufficiently elongated for the required movement of the slide and handle 50.

The handle 50 is arranged exteriorly of the casing bottom wall 19 longitudinally of the casing and between the skids 25—25. Movement of the handle 50 toward the front end ring 21 functions to also move the bag-supporting rod 44, and compress the spring 48 to slacken the bag 31. Upon release of the handle 50, the spring 48 jerks the bag frame 35, the bag-supporting rod 44, the slide 40 and its handle 50 back to their initial positions and vibrates the bag to dislodge the dirt therefrom. The bag 31 limits the return movement of the slide 40 and handle 50 to their initial positions. The bag shaker handle 50 has a surface 55 on which the operator places the palm of his hand to move the slide 40 for collapsing the bag. This surface 55 is inclined outwardly from the casing bottom wall 19 and toward the front end 21, whereby upon exerting a downward force on the handle 50 and movement of the latter is stopped by the pin 51 engaging the ends 56 of the slots 52, 53 and 54 the operator's hand slips off the inclined face 55 of the handle to thereby permit the compressed spring 48 to abruptly return the bag 31 to its taut condition and the handle 50 and slide 40 to their initial positions.

In normal cleaner operation the dirt-laden air is drawn through a suitable cleaning tool unit connected to the inlet port 15 in the end cover 14 and passes into the filter bag 31. The filter bag removes from the air stream the suspended foreign material and the clean air passes outwardly through the side wall 32 and through the perforations in the bag-supporting frame 35 and into the space 57 defined by the surrounding main casing and bag 31. The cleaned air passes into the fan system at the eye of the fan chamber and is exhausted into the space 58 within the casing surrounding the motor. This space is separated from the space around the filter bag by the bulkhead 29. The air then passes through the outlet port 13 into the atmosphere. This operation can continue until such time as the accumulation of foreign material within the filter bag reduces the effective suction of the machine thereby reducing cleaner efficiency, and thereupon it becomes desirable to remove the foreign material from the bag.

The bag-cleaning operation comprises initially removing the front end cap 14. This is accomplished by the operator releasing the cover latch 20 whereupon the cover 14 pivots outwardly at its upper end to permit the downwardly extending lip 16 on the under side thereof to disengage its socket 17. The cleaner is then upended so that the ring or plate 21 lies flush upon the supporting surface which is preferably provided with a paper for receiving dirt. With the machine so positioned the cleaner casing is arranged vertically and the open end of the bag lies flush

with the supporting surface or the paper to receive the dirt to be dislodged from the bag.

To dislodge the foreign material from the bag, the operator places the palm of his hand on the inclined surface 55 of the handle and exerts a downward pressure thereon which moves the slide 40 toward the front end plate 21 of the cleaner or, in other words, toward the supporting surface and the operator can continue movement of the handle and slide downwardly until the pin 51 engages the ends 56 of the elongated slots. During downward movement of the handle 50 and slide 40 the spring 48 is compressed and the bag-supporting rod 44 collapses the bag 31 by movement of the closed end wall 33 toward the front end of the cleaner which slackens the material of the bag as shown in Figure 5.

Downward movement of the handle 50 is stopped when the handle pin 51 contacts the ends 56 of the slots 52, 53 and 54 and upon continued application of pressure on the inclined surface 55, the latter causes the operator's hand to slide off the handle 50 and permits the coil spring 48 to jerk the bag-supporting rod 44 and the bag frame 35 back to their original positions, in which the bag 31 is taut and at the same time the slide 40 and handle 50 are moved back to their initial positions. This abrupt vibration of the bag effects the dislocation of the adhering foreign material within the bag whereupon the dislodged material falls downwardly through the central aperture of the bag ring 34 and accumulates upon the underlying supporting surface. The movement of the bag-shaking handle 50 and slide 40 should be repeated a plurality of times to insure complete cleaning of the bag.

If desired, the operator can firmly grasp the handle 50 and reciprocate the latter to collapse and tighten the bag to dislodge the foreign material from the bag.

After the bag has been adequately cleaned, the operator need only tilt the machine back into its original operating position upon the supporting skids 25—25, replace the cover 14, and the machine is again ready for another normal surface-cleaning operation.

Another embodiment of the invention for operating the filter-shaking mechanism is disclosed in Figures 6 to 8 and comprises a body 60 which is connected to the slide bar 40 by a pin 61 slidably mounted in the elongated slots 53 and 54 in the guide casing 41 and the slot 52 in the casing flat bottom wall 19. Pivotally mounted on the body 60 by means of a pin 62 is a handle 63 having a top wall 64, merging into a reversely curved wall 65, and opposed side walls 66—66. The surface of the top wall 64 of the handle 63 is downwardly inclined for receiving a manually applied force. The handle 63 is normally urged to a projected position as shown in Figure 7 by a torsion spring 67 arranged about the pin 62 and has one end bearing against a lug 68 on the body 60 and the opposite end of the spring 67 rests against the handle top wall 64. Lugs 69 on the handle bottom wall 65 engage the body front wall to limit the outward movement of the handle 63 with respect to the body 60.

In order to rigidly lock the pivoted handle 63 in its projected position shown in Figure 7, a latching device is provided and comprises a latch lever 70 pivotally mounted on a pin 71 supported on a pair of arms 72 in the body 60, and one end of the lever is provided with a pair of lever arms 73 which engage the edge 74 of

the handle 63 and are at all times urged into such engagement by a torsion spring 75 about the pin 71. The opposite end of the latch lever 70 is provided with a lever arm 76 which at all times projects beyond the body 60 toward the casing flat bottom wall 19 and is engageable with an abutment or latch trip pin 77 mounted on the casing flat bottom wall alongside of the elongated slot 52 adjacent the end 56 thereof, whereby when the lever arm 76 engages the trip pin 77 the lever arms 73 are moved out of engagement with the edge 74 of the handle 63.

When it is desired to clean the bag 31 the front end cap 14 is removed and the cleaner upended to its bag cleaning position with the end wall 21 of the casing 10 resting upon a supporting surface which is preferably provided with a paper to receive the dirt dislodged from the bag 31.

The operator places the palm of his hand on the force receiving surface 64 of the handle 63 and exerts a force thereon, and the handle 63 is maintained in its projected position as shown in Figure 7 by the latch lever arms 73 engaging the lower edge 74 of the handle 63. The force exerted on the handle 63 moves the latter and the slide 40 downwardly toward the supporting surface and such movement collapses the bag 31 by shifting the closed bag end wall 33 toward the supporting surface and also compresses the spring 48, as illustrated in Figure 5. When the handle 63 reaches the end of its downward stroke the lever arm 76 strikes the abutment 77 which disengages the lever arms 73 from the lower edge 74 of the handle 63 and permits the latter to move to its collapsed position shown in Figure 8. Upon movement of the handle 63, by the manually applied force, to its collapsed position the top wall 64 of the handle is positioned at a less angle to the casing compared to its projected position and approaches parallelism with the casing flat bottom wall 19 whereby the operator's hand slides off of the handle 63 to release the latter. The compressed spring 48 then moves the bag 31 to its taut condition and the slide 40 and handle body 60 to their initial positions, while the spring 67 pivots the handle 63 back to its projected position shown in Figure 7, for another bag-shaking operation.

If desired the handle 63 may be manually reciprocated by the operator grasping the handle 63 at its top wall 64 and bottom wall 65 but limiting the downward stroke so as not to strike the abutment 77 to trip the latch lever 70, and the handle 63 will be held rigid with respect to the body 60 by the lever arms 73 engaging the handle lower edge 74 and the lug 69 abutting the body 60.

Although the filter-shaking handles 50 and 63 have been described as manipulated by operator's hand, both of the handles can be manipulated by the operator's foot, and if necessary the handles can be relocated toward the front end of the cleaner casing.

I claim:

1. In a suction cleaner, a casing, a dirt filter in said casing, filter-shaking means including actuating means mounted for movement to shake said filter, said actuating means having a force receiving member movable to different degrees of inclination with respect to the direction of movement of said actuating means, locking means maintaining said force receiving member at one inclination to said direction of movement to receive an operator applied force for moving said actuating means in one direction, and means operative toward the end of movement of said

actuating means in said one direction to render said locking means inoperative and permit movement of said force receiving member to a less inclined position by said operator applied force.

2. In a suction cleaner, a casing, a dirt filter in said casing, filter-shaking means including a slidably mounted member and a force receiving member movable with said slidably member, said member movably mounted on said slidably member to different degrees of inclination with respect to the direction of movement of said slidably member, locking means maintaining said force receiving member at one inclination to the direction of movement of said slidably member to receive an operator applied force for moving said slidably member to shake said filter, and means on said casing operative toward the end of movement of said slidably member to render said locking means inoperative and permit movement of said force receiving member to a less inclined position by said operator applied force.

3. In a suction cleaner; an elongated casing; said casing having an exhaust end and a suction end; a filter bag supported within said casing; means for attaching the open end of said filter bag to the interior of the suction end of said casing with its closed end extending toward the exhaust end of said casing; a slide bar mounted for reciprocation on said casing; said slide bar having a force applying end and a force transmitting end; the force transmitting end of said slide bar being positioned adjacent the closed end of said filter bag and the force applying end being positioned adjacent the exhaust end of said casing; a support at all times rigidly connecting the closed end of said filter bag to the force transmitting end of said slide bar; manually engageable force applying means attached to the force applying end of said slide bar; springs means connected to said slide bar so as to bias it, said support, and the closed end of said filter bag toward the exhaust end of said casing to normally maintain said filter bag in a taut condition; the arrangement being such that a manual application of force to said force applying means in a direction to move said slide bar, support and the closed end of said filter bag toward the suction end of said casing against the bias of said spring means will move said slide bar, support and the closed end of said filter bag toward the suction end of said casing to collapse said filter bag, and the removal of the aforesaid manually applied force will cause said spring means to return said slide bar, support, and the closed end of said filter bag toward the exhaust end of said casing and snap said filter bag to its taut condition to dislodge any dirt accumulated on its interior.

EUGENE L. SNYDER.
